By his Attorney,

INVENTOR,
Levi Murray,
J. S. Brown.

UNITED STATES PATENT OFFICE.

LEVI MURRAY, OF CENTRE HALL, PENNSYLVANIA.

BOW-TOP FOR CARRIAGES.

SPECIFICATION forming part of Letters Patent No. 251,626, dated December 27, 1881.

Application filed June 17, 1881. (No model.)

To all whom it may concern:

Be it known that I, LEVI MURRAY, of Centre Hall, in the county of Centre and State of Pennsylvania, have invented an Improved 5 Bow-Top for Carriages; and I do hereby declare that the following is a full and exact description thereof, reference being had to the accompanying drawings, making part of this specification—

10 Figure 1 being a side view of a three-bow top for carriages and vehicles provided with my improvement, the view representing the top as raised or extended; Fig. 2, a side view of the same as when folded.

15 Like letters designate corresponding parts in both figures.

My invention consists in the combination, preferably with the middle bow of a carriage-top, of short bows hinged or pivoted respectively to the front and rear sides of the said middle bow, the said short bows being jointed near their hinge or pivot supports, and connected at points above the said joints by braces with the middle bow, substantially as herein- 25 after specified, whereby the leather top and trimmings are supported between the main bows, and yet are allowed to fold in between the said main bows, and the whole top is extended and folded in the usual way, and held 30 extended by the usual top-joints.

In the drawings, A A represent the front and back bows of a three-bow carriage-top, and B the middle bow thereof. These are all of ordinary construction, and they have the 35 usual top-joints (not shown in the drawings) for extending the top.

To the middle bow, B, in a suitable position, as at a a thereon, short bows C C are hinged or pivoted, so that when the top is extended 40 they will assume oblique positions, substantially as shown in Fig. 1, and support the top-trimmings D between the main bows, and also allow the main bows to be spread farther apart than usual, thus making a more extended carriage-top. These short bows are not

only hinged or pivoted at their feet to the middle bow, but are themselves jointed, as at b b, at some distance from the hinge-pivots a a; and to these bows are hinged or pivoted, as at c c, above the joints b b, braces E E, which at 50 their other ends are hinged or pivoted to the middle bow, as at d d, above the foot-pivots a a of the short bows. The length and positions of these braces, and the relative positions of the joints and pivots a a, b b, c c, and 55 d d, are such that when the top is folded the short bows will not only shut close down by the sides of the middle bow, but will drop considerably below the main bows, and thus be entirely out of the way of the leather and 60 trimmings of the carriage-top, which fold without hindrance between the main bows, as indicated in Fig. 2.

These bows, thus arranged and operating, work with perfect freedom, never interfering 65 with the folding or extending of the carriage-top, and when raised, as in Fig. 1, though they are jointed at b b, yet they are in a straight line, from which they cannot deviate, and thus are held securely and firmly on the dead-points 70 of the said joints, which may be rule or elbow joints bending only downward. The bows likewise lie compact when the top is folded down, and are not in the way, and their expense is but little. An important advantage 75 in their use is their perfect self adjustment, requiring no care whatever in folding or extending the top.

What I claim as my invention is—

The jointed short bows C C, hinged or pivoted 80 to the main bow B, in combination with the said main bow and pivoted connecting-braces E E, substantially as and for the purpose herein specified.

The foregoing specification signed by me 85 this 11th day of April, 1881.

LEVI MURRAY.
